UNITED STATES PATENT OFFICE

GEORGE HENRY BULTMAN AND JAMES C. HORGAN, OF ST. PAUL, MINNESOTA

IRONING BOARD

Application filed October 7, 1927. Serial No. 224,719.

Our invention relates to ironing boards, and the main object is to provide a simple, highly efficient, portable, and inexpensive ironing board, embodying certain improvements as hereinafter described and illustrated in the accompanying drawing, in which,—

Fig. 1 is a top view of our improved ironing board in operative position grasping the edge of a table top.

Fig. 2 is a side elevation of Fig. 1.

Fig. 3 is a transverse sectional elevation of the ironing board about as on line 3—3 in Fig. 2.

Fig. 4 is an enlarged sectional view as on line 4—4 in Fig. 3.

Referring to the drawing by reference numerals, 5 designates an ironing board of the conventional type, usually elongated and tapered at its outer end as shown, the rear end of the board being cut square and slotted longitudinally and centrally as 6 (Fig. 1). 7 is a single leg or prop member pivoted at 8 in a transverse metal bracket 9 suitably fixed to the under side of the board at the forward terminus of the slit 6. The prop 7 is in effect a beam lever pivoted as described at 8, and rearward of which it comprises a short lever arm terminating in a downwardly and rearwardly opening notch 10 and the longer forwardly projecting part of the prop being comparatively long and arranged to engage the floor 16 as in Fig. 2. When the said prop is in the angular position shown, it is at this time the notch part 10 is approximately parallel to the top surface of the rear end of the board 5. The latter being placed horizontally under the outer edge portion of the top 11^T of a table 11. The notched part 10 simultaneously engages the top surface of 11^T as shown in Fig. 2.

We prefer to provide a strip of suitable padding material 12, probably felt, on the top of board 5, and adjacent its rear edge where it engages the table top or similar element. Likewise a padding material 12^A is provided in the notched part 10 of the prop.

It is obvious that when the prop 7 is in

the gripping position shown in Fig. 2 and table top 11^T is comparatively high, the lower end of the prop may not reach the floor. To provide a proper contact on the floor we pivot on a bolt 14 a contact lever 15 of which one lever arm is longer than the other. Thus the operator may loosen the nut of bolt 14 and swing lever 15 with either end toward the floor 16 for proper supporting level herewith as at the right hand level 16 in Fig. 2. The operator then simply tightens the nut of bolt 14 to hold lever 15. Said right hand level 16 is assumed in this case to be the floor on which table 11 rests.

The metal bracket 9 previously mentioned consists preferably of a one-piece casting fixed transversely across the underside of board 5 by a number of wood screws 17 or equivalent means and its opposite ends comprise each an upwardly extending terminus 9^L preferably inserted in a notch and flush with the outer edge of the board. The central part of this bracket comprises 2 spaced downwardly directed lugs 9^F bored for the pivot bolt 8 to pivotally retain the prop 7 between them. Above these lugs the casting is formed in inverted U-shape at 9^R in Fig. 3, forming a yoke effect, said yoke having a rearwardly and upwardly inclined face 9^F serving as a stop for the upper edge of the prop 7. When the latter is swung to its angular holding position as in Figs. 2 and 4 the rear end of said prop is of course above the level of the board 5 and its notch in position to engage the top edge portion of a table top, window ledge, or similar stationary element.

We are aware that a number of patents on ironing boards of similar general appearance have been issued, but we believe the reinforcing a pivot member 9 is new and useful. The adjustable lever prop 15 is another feature of this invention. It is obvious that the angular stop face 9^F of casting 9 is a positive stop for the member 7, insuring rigidness of the members 7 and 5, and also absolutely preventing splitting of the ironing board proper. Furthermore the construction of bracket 9 is such that the rear end of the board is positively held in a flat

plane and cannot bulge or warp, and this is accomplished by said bracket only, no unsightly cross pleats being necessary on the board. The board may be of any suitable length and width and tapered as desired at its front end but in general use such boards are usually about five feet long and one foot wide.

It is obvious that the major part of the ironing board, in fact all of it forward of its pivot, is available for ironing purposes and garments to be ironed can be slipped upon it and easily manipulated for ironing purposes because there are no leg supports, brackets, or other obstacles on said board forward of the bracket 9.

We claim:

In combination with an ironing board provided with a slot extending inwardly from one end thereof and a prop pivoted to the board adjacent the terminus of said slot and movable therein, said prop having a rearwardly and downwardly opening notch at its rear end and movable into closing position relative to the top rear edge part of the board to grip a horizontal element; said pivot means for the prop comprising a metal cross member fixed to the under side of said board and having an integral inverted U-shaped yoke part at its center with an angular face engaging one end of the slot and arranged to be engaged by the prop when the latter is in an angular position to the board, and means comprising lugs at the ends of the cross member engaging the opposite edges of the board.

In testimony whereof we affix our signatures.

GEORGE HENRY BULTMAN.

JAMES C. HORGAN.
